Primary Examiner — Stacia Cadmus(74) *Attorney, Agent, or Firm* — Richard B. O'Planick(57) **CLAIM**

The ornamental design for a tire sidewall, as shown and described.

DESCRIPTION

The sole FIGURE is a front view of a tire sidewall showing our new design.

In the drawings, the broken lines showing of the tire tread, inner bead and the peripheral boundary between the tire tread and the sidewall in the sole FIGURE depict environmental subject matter and form no part of the claim.
